CLAIM

The ornamental design for a removable shim, as shown and described.

DESCRIPTION

FIG. 1 is a front perspective view of a removable shim showing my new design.

FIG. 2 is a top view thereof;

FIG. 3 is a bottom view thereof;

FIG. 4 is a back side view thereof;

FIG. 5 is a front side view thereof;

FIG. 6 is a right side view thereof; and,

FIG. 7 is a left side view thereof.

The broken lines in the figures represent portions of the article which form no part of the claimed design.
